UNITED STATES PATENT OFFICE.

PHILIPP BOCH, OF NEW YORK, N. Y.

BOTTLE-HOLDING ATTACHMENT FOR BOTTLE-WASHING MACHINES.

No. 893,975.

Specification of Letters Patent.

Patented July 21, 1908.

Application filed June 5, 1907. Serial No. 377,291.

To all whom it may concern:

Be it known that I, PHILIPP BOCH, a citizen of the United States, residing in New York, in the borough of Queens and State of New York, have invented certain new and useful Improvements in Bottle-Holding Attachments for Bottle-Washing Machines, of which the following is a specification.

This invention relates to an improved bottle-holder for bottle-washing machines.

The object of this invention is to obviate the danger of accidents due to breaking of the bottles in bottle-washing machines by applying to the housing of the water-supply tube a permanently attached, forwardly-extending holder on which the bottle is supported while the cleaning operation takes place, so that it is less exposed to breaking or bursting than when holding it by hand against the housing of the water-supply tube of the bottle-washing machine; and for this purpose the invention consists of a bottle-holding attachment for bottle-washing machines, which comprises a forwardly-extending arm, means for attaching the same to the housing of the water-supply tube and a segmental support for the bottle to be washed attached to the outer end of the arm, said arm having a water-shedding rim at an intermediate point of its length, as will be fully described hereinafter and finally pointed out in the claims.

In the accompanying drawing, Figure 1 is a perspective view of a bottle-washing machine with my improved bottle-holding attachment in position on the housing of the water-supply tube, Fig. 2 is a side view of the bottle-holding attachment, drawn on a larger scale, Fig. 3 is a vertical transverse section on line 3, 3, Fig. 2, and Fig. 4 is an end elevation of Fig. 2.

Similar letters of reference indicate corresponding parts throughout the several figures.

Referring to the drawing, *a* denotes the housing of the water-supply tube and *b* the wipers of a bottle-washing machine. The wipers *b* are mounted upon a tubular spindle which forms the water-supply tube and is rotated by the belt and pulley mechanism illustrated. The housing *a*, which carries the mouthpiece against which the bottle is held during the washing operation, is guided on parallel guide-rods and pressed in backward direction by means of a foot-operated stirrup *s* when the bottle is placed in position, and moved in forward direction by releasing the

stirrup when the bottle after being cleaned is to be removed from the wipers. When the housing is moved backward the wipers are uncovered and spread apart by means of a spring in order to conform to the interior of the bottle as described in Letters Patent No. 856,191 granted to me under date of June 14, 1907.

To the rear part of the housing *a* is applied a slightly curved, forwardly-extending bottle-holding arm *c* by means of clips *d*. Said clips are formed of semicircular lower parts *d*¹ cast integral with the arm *c*, detachable semicircular upper parts *d*², and clamping screws *d*³. The front clip is somewhat larger than the rear clip so as to provide for the larger diameter of the forward part of the housing *a*. The bottle-holding arm *c* is provided with a slightly curved portion *c*¹ adjacent to the fastening clips *d*, and at its outer end with a segmental rest *f*, the slotted shank *f*¹ of which is guided in vertical ways *f*² at the front ends of the arm *c* so as to be adjusted into higher or lower position by means of a clamping screw *f*³, as shown clearly in Figs. 2 and 4. The ends of the segmental rest *f* are provided with tubular cushions *g* of soft rubber so as to prevent a too violent concussion of the bottle with the rest-piece when the bottle is placed in position on the holding attachment. When larger bottles, such as champagne or other bottles, are to be cleaned, the smaller holder is removed and replaced by one of larger size.

At a point of the arm *c* intermediately between the front fastening clip *d* and the holder *f* is arranged a raised rib *r*, which extends around the entire arm and which serves for the purpose of shedding the water delivered by the water-supply tube and preventing it from running along the arm towards the rest-piece at the end of the same.

After the bottle-holding attachment is applied by the clips *d* to the housing *a* of the water-supply tube, the attendant places the bottle with its mouth against the mouth of the housing and with its body on the segmental rest-piece and holds it simply with slight pressure thereon so as to retain the bottle in position on the holding arm. The bottle is then cleaned in the usual manner by depressing the stirrup, in order to move the housing of the water-supply tube back and the wipers into the bottle, the supply of water combined with the rotary motion of the wipers cleaning the bottle in the usual

manner. The stirrup is then released and the bottle removed.

By using the bottle-holding device the operation of cleaning bottles is greatly facilitated and the latter are not so liable to be broken as when they have to be held by hand against the housing of the water-supply tube.

Having thus described my invention, I claim as new and desire to secure by Letters Patent:

1. In a bottle-washing machine, the combination, with the housing of the water-supply tube, of a bottle-supporting arm, and 15 clips embracing said housing and by which said arm is attached to the same, said clips being formed of semi-circular lower parts integral with said arm, and detachable semi-circular upper parts.

2. A bottle-holding attachment for bottle-

washing machines, consisting of a curved arm, clips at its rear portion for attaching it to the housing of the water-supply tube, and a segmental bottle-supporting rest-piece at the front end of the arm.

3. A bottle-holding attachment for bottle-washing machines, consisting of an arm, 25 clips at its rear portion for attaching it to the housing of the water-supply tube of the machine, a segmental bottle-rest at the front 30 end of the arm, and a raised water-shedding rib at an intermediate point of the arm between the front clip and rest-piece.

In testimony, that I claim the foregoing as my invention, I have signed my name in presence of two subscribing witnesses.

PHILIPP BOCH.
